JEWELRY FINDING

Bernard Bernstein, 3224 Bronx Blvd.,
Bronx, N.Y. 10467

Filed Mar. 26, 1973, Ser. No. 345,013

Term of patent 14 years

Int. Cl. D11—01

U.S. Cl. D45—19 R

The figure is a plan view of a jewelry finding, showing my new design.

The opposite surface is smooth and plain.

The side edge is of conventional thickness and plain.

I claim:

The ornamental design for a jewelry finding, as shown and described.
